CARTRIDGE FED ANIMAL INSECTICIDE
APPLICATORCharles H. Murray, 1110½ S. Main, and James W. Wallace, 801 Ada, both of Scott City, Kans.
Filed July 21, 1960, Ser. No. 44,361
4 Claims. (Cl. 119—157)

This invention relates to an insecticide applicator for livestock.

One main difficulty of the insecticide applicators presently in use involves the re-filling of the insecticide reservoir commonly attached or made a part of the apparatus. In the past, the user, who is usually a farmer, rancher or stock feeder, has let the present type of applicator become ineffective as such because they permit the applicator to become dry. The reason for this is primarily because of the difficulties in re-filling the apparatus, that is, it takes considerable time and effort, and further requires the use of special tools, re-filling cans, funnels and the like.

Hence, one main object of this invention is to provide in combination a replaceable cartridge containing insecticide which will permit the user to merely remove the empty cartridge, replacing it with a full cartridge, thereby eliminating the objectionable features referred to above.

Another object of this invention is to provide a cylindrical-type applicator which will house a cartridge-type filler and yet permit a controlled flow of the insecticide over the entire outside area of the applicator, resulting in effective application of the insecticide to the animal.

A further object of this invention is to provide a means for suspending a series of such cylindrical applicators so that a plurality of such can be put into use from a single supporting foundation, in such a manner as to permit practically the entire outer area of said cylindrical applicator to be available for contact.

A still further object of this invention is to provide a simple and practical insecticide applicator of low cost, comprised of a minimum number of elements, each of which may be replaced by the user inexpensively.

Further objects and advantages of the invention will become apparent from a description of the apparatus itself, along with the accompanying drawing and claims.

FIG. 1 is a front view, showing the applicator along with its rigid frame construction.

FIG. 2 is a sectional view taken along line 2—2 and showing the insecticide cartridge in place within the applicator.

FIG. 3 is a cut-away view of a portion of the bottom of said cartridge showing an opening covered by a blister seal.

FIG. 4 is a cut-away view of the inside liner 4 of the cylinder housing also taken along part of line 2—2 showing perforations or weep holes which permit the insecticide to escape outside the housing to saturate the absorptive material around which the wire mesh has been placed, said view considered with the cartridge 6, absorptive material 3, and wire mesh 14, all removed.

Like characters of reference indicate like parts in the different views in the drawing.

Turning first to FIG. 1 of the drawing, a metal strip or angle iron 7 has been welded to two metal rings 8 and 9. These rings 8 and 9 are made out of heavy gauge metal of sufficient size to permit the housing of the entire cylinder. In order to prevent the cylinder from slipping, a metal strip 12 has been brazed or welded across the diameter of the metal ring 8.

Turning now to FIG. 2, it will be noted that a hollow metal cylinder 4 of sufficient diameter to permit the cartridge 6 to be inserted, has been used as a form around

2

which an absorptive material 3, such as pressed felt, has been wrapped. This absorptive material may be spot glued to secure it to the outer portion of the hollow metal cylinder 4. Around the absorptive material 3 has been placed a heavy wire mesh 14, which may be securely fastened by tie wires, spot welding or other satisfactory conventional means not shown. This wire mesh 14 should be snugged tight across the absorptive material 3 to prevent any slippage or movement between the absorptive material 3 and the wire mesh 14.

Around the inner periphery of the hollow metal cylinder 4 and adjacent that end adjacent the metal ring 9 has been placed a suitable thickness of absorptive material 5, similarly of pressed felt or other suitable material, which may be glued, the purpose of such absorptive material 5 being more particularly set forth hereinafter.

The end of the hollow metal cylinder 4, adjacent the metal ring 8, has been sealed completely. The walls of said hollow metal cylinder 4 have a plurality of weep holes 11 which may be approximately $\frac{1}{16}$ to $\frac{1}{8}$ inch in diameter and located within the middle $\frac{2}{3}$ of said cylinder, as more particularly shown in FIG. 4 of the drawing. These weep holes 11 extend completely around the hollow cylinder 4 within this middle two-thirds area, so that when an animal rubs against the applicator so as to cause the entire applicator to swing in an arc, the insecticide will flow continuously out of the weep holes. As will be seen hereinafter, when the insecticide escapes from the cartridge 6, it will flow into the open area between the outside wall of the cartridge 6 and the inside wall of the hollow metal cylinder 4. It should be recognized that each end of the metal strip 7 from which the applicator is suspended is attached to any commonly known type of swivel connection which would permit radial movement of the entire apparatus. As stated, it is the inventors' conception that a plurality of these applicators could be used and would be suspended by a single common metal strip such as the strip 7. In any event, the insecticide inside the cartridge 6 will flow out into the inside wall of the open area as stated. This insecticide will then escape through the weep holes in the cylinder 4 directly to the absorptive material 3, thus saturating the absorptive material, which will permit effective application of the insecticide upon any animal making contact.

The insecticide inside the cartridge will continue to flow into the area between the hollow cylinder 4 and the outer wall of the cartridge 6. It will in turn flow out the weep holes until the fluid level is almost exhausted, and it is believed that the movement of the apparatus, actuated by an animal brushing against it, will be sufficient to keep the insecticide in agitated movement so that it will drain completely in the fashion described. The wire mesh 14 has a two-fold purpose, in that it keeps the absorptive material intact and scratches the hide of the animal.

The replaceable insecticide cartridge 6 is made of a thin wall metal or plastic completely sealed at both ends, however, the bottom end of the cartridge has one or more holes 13 to permit the insecticide to flow out of the cartridge in the manner aforesaid. I prefer at least two holes so that during the cold season, twice as much area will be available for the insecticide to flow, whereas in the warm season only one hole will be used. This preference is based on the fact that the insecticide during the cold season has a high viscosity and the flow will be somewhat impeded.

In order to permit the insecticide cartridge to be portable without danger of leaking, these holes have been covered by a blister-like covering 10, which may be of wax, paraffin, plastic or some other suitable material which may be removed with a scraping of the fingernail when the cartridge is to be inserted for use. One end

of the cartridge 6 has a flanged portion 15 which, when the cartridge is inserted, fits snugly against the absorptive material 5 located on the inner portion of the hollow metal cylinder 4. This serves two purposes, in that the tight fit between the above elements will retain the cartridge in place and also prevent the insecticide from flowing in any other manner than through the perforations 11. There will be some saturation of this absorptive material 5, however, it has been experienced that such saturation will nowhere be complete during the time required for completely exhausting all insecticide out of the cartridge 6 and onto the absorptive material 3.

In the illustration shown in the drawing, which has been put in actual practice, no fastening device is necessary if the cartridge 6 fits snugly against the absorptive material 5 lining the inside of the cylinder 4.

Having thus described one illustration of our invention, along with the component features and elements thereof, it should be understood that the above description is meant for purposes of describing and illustrating the invention in the best possible manner, but is not meant to limit its features in any way, as variations of the structure may be made within the scope of the claims.

What we claim is:

1. In combination, an insecticide applicator comprised of a cylinder having one open end and a plurality of openings in the side walls, absorptive material surrounding said cylinder, heavy wire mesh surrounding said absorptive material, additional absorptive material secured around the inner periphery of said cylinder near its open end only, a sealed removable insecticide filled cartridge inserted within said cylinder and having one flanged end which fits tightly against said additional absorptive material to retain said cartridge within the cylinder, a plurality of weep holes in the bottom end of said cartridge for at times permitting the insecticide to escape into said cylinder, removable seals placed over said weep holes to prevent flow of contents until said cartridge has been inserted.

2. In combination, an insertable cartridge, a hollow cylinder with one open end for at times receiving said cartridge, absorptive means about the outer surface and also around the inner periphery of one end of said cylinder, a plurality of weep holes in that remaining portion of said cylinder not having absorptive material on its inner periphery, sealed end holes in said cartridge permitting the insecticide to exude when unsealed, said absorptive means being impregnated by the flow of such insecticide whereby an animal contacting said absorptive material will receive an application of insecticide.

3. A cylindrical insecticide applicator comprised of wire mesh having absorbent material about its inner periphery, a perforated hollow cylinder sealed at one end and having absorbent material about the inner periphery of the other end, a sealed insecticide cartridge for insertion into said hollow cylinder and having means for unsealing said cartridge when inserted, said cartridge having an enlarged portion at its outer end cooperating with the adjacent absorbent material inside said hollow cylinder to retain said cartridge in its inserted position.

4. An insecticide applicator comprised of a hollow cylinder having absorptive material about its outer surface and one end portion of its upper surface, wire mesh wrapped around said outer absorptive material, weep holes located about the surface of said hollow cylinder, a sealed container insertable into said hollow cylinder, said hollow cylinder having one end sealed, a plurality of openings about the lower end of said sealed container with means for sealing and unsealing said openings, and frame means around the said wire mesh to permit said applicator to be mounted.
